(Continued)

Primary Examiner — Cathron C Brooks*Assistant Examiner* — Ian F Whitmore(57) **CLAIM**

The ornamental design for a display screen with printer icon, as shown and described.

DESCRIPTION

FIG. 1 is a front view of a display screen with printer icon showing the new design enlarged and without broken lines for clarity of illustration; and,

FIG. 2 is a front view of a display screen with printer icon showing the new design.

The irregular broken-line perimeter shown in FIG. 2 illustrates a display screen and forms no part of the claimed design. The remaining broken lines illustrate portions of a graphical user interface and form no part of the claimed design.

1 Claim, 2 Drawing Sheets(56)
